DESIGN FOR AN OPTICAL FRAME

Edward Salvage, New York, N. Y.

Application June 10, 1944, Serial No. 113,953

Term of patent 7 years

(Cl. D57—1)

To all whom it may concern:

Be it known that I, Edward Salvage, a citizen of the United States and a resident of the city of New York, in the county of New York and State of New York, have invented a new, original, and ornamental Design for an Optical Frame, of which the following is a specification, reference being had to the accompanying drawing, forming a part thereof.

Fig. 1 is a top plan view of an optical frame showing my design

Fig. 2 is a front elevational view thereof.

I claim:

The ornamental design for an optical frame, substantially as shown.

EDWARD SALVAGE.
